APPARATUS FOR THE PRODUCTION OF
MUSICBenjamin F. Miessner, Millburn Township, Essex
County, N. J., assignor to Miessner Inventions,
Inc., a corporation of New Jersey

Application March 7, 1934, Serial No. 714,385

18 Claims. (Cl. 84—246)

This invention relates to the production of music from tuned vibrators, and more particularly to improved means and methods for exciting the vibrations of such vibrators. As to certain of its subject matter this application is a continuation in part of my co-pending application, Serial Number 662,697, filed March 25, 1933.

In the tuned vibrator type of musical instrument a commonly employed method of setting each vibrator into vibration is impulse excitation—e. g., the stroke of the hammer in the playing of the piano, the pluck of the plectrum in the playing of the mandolin, etc. It is a broad object of the instant invention to provide improved means and methods for impulse excitation of the vibrators.

The use of electrical or electrically controlled means for exciting the vibrators has certain advantages, such for example as the opportunity to locate the vibrators remotely from the playing keys or the like, and various such exciting means are known. It is an object of my invention, however, to provide improved such means for impulse excitation of the vibrators.

An opportunity for effective control over output tone quality in respect of inception and damping characteristics is afforded by the selective availability of impulse and oscillatory excitation of the vibrators. It is a further object of my invention to provide simple and economical means for selectively producing impulse and oscillatory excitation of the vibrators.

It is known that characteristics of the excitation, whether impulse or oscillatory, affect various qualitative characteristics of the vibrator vibration and output sound aside from those of inception and damping. It is an object of my invention to provide improved excitation control means and methods whereby to effect control over such qualitative characteristics of the output sound. A more specific object is the provision of improved excitation control means whereby to effect control over the timbre, or harmonic structure, of the output sound.

A general object is the provision of an improved instrument whereby output tones of a variety of qualitative characteristics may be produced.

Other and allied objects will more fully appear from the following description and the appended claims.

In such description reference is had to the accompanying drawings of which:

Figure 1 is a partly perspective, partly dia-

grammatic view of one embodiment of my invention in simple form;

Figure 2 is a like view in slightly modified form;

Figure 3 is a partly perspective, partly diagrammatic view of my invention in more complete form and adapted effectively to control the timbre of the output sound;

Figure 4 is a like view in somewhat modified form; and

Figure 5 is a partly cross-sectional, partly dia- 10
grammatic view of another embodiment of my invention; and

Figure 6 is a like view of a further embodiment 10
of my invention.

It is well known that vibrator exciting forces 15
may be translated from electric currents, such
a current energizing an exciting device imme-
diately associated with the vibrator—for example
an electromagnet which directly attracts the
vibrator or which moves a hammer or the like 20
to strike the vibrator. When such translation is
employed in simple impulse excitation only that
flow of electricity which immediately ensues the
inception of flow is useful, and the continuation
of flow for any appreciable length of time is 25
wasteful and usually detrimental. Thus the
continuation of flow through such an electro-
magnet as abovementioned tends to cause heating
thereof and compels its design in far more
generous proportions than are required to with- 30
stand the limited useful portion of the flow. It
is therefore desirable to energize the electromag-
nets or the like by a flow of electricity of auto-
matically limited duration.

In my application Serial Number 637,403, filed 35
October 12, 1932, now Patent 1,979,633, granted
October 31, 1933, I showed electromagnets mov-
ing hammers adapted to strike the strings; the
current energizing the electromagnets being gen- 40
erated by magneto-electric generators attached
to, and operated only by movement of, the playing
keys. The playing keys being capable of only
limited movement, the desired limitation of cur-
rent duration was obtained. It is frequently de- 45
sirable, however, that the keys function only
to control, and not to generate, the current or
flow of electricity, the latter itself being derived
from a continuously operative source. The pres-
ent invention accordingly comprehends several 50
embodiments wherein the exciting devices im-
mediately associated with the vibrators are en-
ergized by the flow, of limited duration, of elec-
tricity derived from such a source.

In the first-illustrated of these embodiments 55
there is employed an electrical capacity adapted

to store a predetermined quantity of electricity from the source, the exciting device immediately associated with the vibrator being energized by the flow of that quantity of electricity into or 5 out of the condenser. This is illustrated in Figure 1. Herein the vibrator is shown as the tuned string 1, strung for example over triangular bar 2 and bridge 10 between tuning- and hitch-pins not herein necessary to show. This figure by 10 way of example shows the bridge 10 secured to a soundboard 11, providing direct mechanico-acoustic translation of string vibration into sound. The exciting means immediately associated with the string is shown as the electromagnet 4 positioned in slight spaced relationship thereto; the electrical capacity is shown as the condenser 3. Between a first end of the condenser and a first end of the electromagnet is 15 illustrated the switch 5 comprising the blade 5' and the contact 5'', which switch may be key-controlled and is biased to an open position. The second end of the capacity 3 is shown connected to ground, which is a convenient designation for a first terminal of the battery or other source of 20 electricity 6. The second end of the electromagnet is also connected to ground, so that upon closing of the key-switch 5 the condenser and electromagnet will be connected in series and such quantity of electricity as may then be stored 25 in the condenser will be discharged through the electromagnet. In order that the condenser 3 may normally have stored therein a quantity of electricity, the battery or other source 6 is connected through a resistance 7 to a contact 5''' 30 included in the key-switch 5 and arranged to be impinged against by the switch blade 5' when the switch is open. The voltage of the source 6 will determine the quantity of electricity stored in the condenser 3; and if desired this quantity 35 may be regulated by the potentiometer 9 included in association with the source 6 for regulation of its effective voltage.

The illustrated connection of condenser 3 to ground is through a switch 17. This may be 40 thrown if desired to the left to connect the condenser to ground through the source 6. Under these conditions the condenser is maintained normally discharged of electricity and will be charged with the predetermined quantity upon 45 closing of the switch blade 5' against the contact 5''. The action is entirely similar to that occurring with switch 17 in the illustrated position, excepting for the immaterial opposition of direction of flow through the electromagnet and 50 for the fact that the flow now must pass through the effective internal resistance of the source 6.

In series with the electromagnet 4 is illustrated a variable resistance 8. It is convenient to denote by the symbol R the sum of the value of this 55 resistance 8 and the residual resistances of the circuit closed by closing of the key-switch 5—i. e., the effective internal resistance of the electromagnet, and the effective internal resistance of the source 6 if this is rendered in series with the condenser 3 by throwing of switch 17 to the left. The characteristics of the flow of electricity occurring upon closing of the key-switch 5 will be determined by the relative values of R, of the capacity of 3, and of the inductance of 4. Thus 60 if R be less than a critical value of $2L^{\frac{1}{2}} C^{-\frac{1}{2}}$ (L being the inductance of 4 in henries and C the capacity of 3 in farads) the flow will be of an oscillatory nature; otherwise it will be aperiodic. When the flow is oscillatory it consists in a 65 train of oscillations whose frequency, initial am-

plitude and rate of decay depend on the mentioned values; when aperiodic it consists in a single current pulse which rapidly rises to a maximum value and then decays, the maximum value, the rate of arrival thereat, and the rate of decay 70 therefrom being determined by the mentioned values.

For simple impulse excitation I employ sufficient resistance in 8 to render the flow aperiodic—i. e., to raise R to at least the critical value above-mentioned. With the source 6 adjusted to any given voltage output, and with fixed inductance and capacity values of 4 and 3, respectively, the maximum impulse excitation will be obtained when R is of such critical value. An increase 75 from this value, as by the increase of the resistance of 8, provides a convenient means of control whereby to reduce the strength of the impulse excitation.

Excitation of a modified nature is obtained if R be made appreciably less than the critical value, either by reduction of the value of 8 or by its complete short-circuiting as by the switch 18 shown connected therearound. In this event the flow upon closing of the key-switch 5 will be 80 oscillatory and its frequency may be tuned by variation of L or C, the condenser 3 having been illustratively shown variable. The excitation of the string produced by the flow will then of course be oscillatory and will (assuming the electromagnet 4 to be unpolarized) be bicyclic with respect to the flow. Therefore if the flow be tuned to half the fundamental or other partial vibrational frequency of the string, the frequency of excitation will coincide with that partial frequency, and the excitation will approximate to that obtained by the well-known method of energizing a string exciting magnet with continuous alternating current of the string's own frequency. The distinction lies in the damped nature of the 85 flow in the instant case, and may of course be minimized by making as low as possible the residual resistance of the circuit. The switch 18 will thus be seen to provide a very convenient means for selecting between impulse and oscillatory excitation.

It has thus far been assumed that the electromagnet 4 is unpolarized. It should be understood, however, that in the carrying out of my invention the electromagnets may if desired be 90 permanently polarized, as by permanent magnetization of the core 4' of the electromagnet 4 of Figure 1. Preferably in such case the permanent polarization should be of at least the effective strength attained at peak by the temporary polarization resulting from the above discussed flow of electricity through the electromagnet. It is to be noted that with the electromagnet so polarized an oscillatory flow of electricity therethrough will produce an excitation 95 which is cyclic, rather than bicyclic, with respect to the flow.

In Figure 1 the electromagnet 4 is of simple form with fixed core 4' and is intended to influence the string by magnetic induction. In 100 Figure 2, however, I have alternatively illustrated an electromagnet 4 having a movable core 4'' adapted to be moved upwardly by the electromagnet upon the flow of electricity through the latter and therefore to impinge against the string 105 and excite the same by mechanical impact. The core 4'' may be surmounted by a tip 4''' of rubber or the like, forming a hammer head suitable for such impact. The electromagnet upon energization thereof tends to centralize the core 4'' verti- 110

cally therewithin; the core, being normally maintained as by gravity in a lower than centralized position, is moved upwardly by the energization and caused by its momentum to overshoot such centralized position and strike the string. In this case in which the core of the electromagnet is movable and intended mechanically to influence the string, the resistance 8 should be maintained at at least a sufficiently high value to insure a 10 periodicity of the flow through the electromagnet. It may as before, however, be increased from this value to reduce the strength of the excitation. For maximum efficiency the principal portion of the flow should occur before the core 4" in its 15 upward movement has passed a centralized position within the electromagnet.

It will be appreciated that while a specific arrangement has been shown in Figure 1 for maintaining the condenser in readiness to produce the 20 flow through the electromagnet (i. e., normally charged or discharged, according to the position of switch 17) other arrangements may be employed. Thus in Figure 2 I have illustrated one 25 wherein the resistance 1, instead of being connected to a separate contact 5''' on the key-switch 5, is connected to the blade 5' of that switch. With this connection the desired normal condition of the condenser 3 is obviously maintained while the key-switch 5 is open. When 30 the key-switch is closed the condenser will as before produce the flow through the electromagnet; there will also then take place through the electromagnet, however, a steady current determined by the voltage of battery 6 (as adjusted 35 by potentiometer 9) and the combined resistance value of 7 and R. In order to reduce the magnitude of this steady current the resistance value of 7 may be made as high as consistent with satisfactory rapidity in attainment of normal condition by condenser 3 upon opening of the key-switch 5.

In Figure 3 I show a more elaborate string excitation system, again employing condenser discharge or charge current. The figure shows a 45 plurality of strings 1, in order that the circuits for a complete instrument may be indicated. For each string there may be provided a separate condenser 3; each of these may be maintained normally charged or discharged, and discharged or charged (as the case may be) at will through 50 the string exciting circuit, by a resistance 7 from the voltage source 6 and by a key-switch 5, as in Figure 1.

The string exciting circuit for each string is 55 provided with a plurality of branches, an electromagnet being included in each branch of each such circuit. Thus the contact 5'' of the switch for each string is shown connected to both an electromagnet 4a and an electromagnet 4b, these 60 electromagnets being positioned adjacent respectively different portions of that string. In series with each electromagnet 4a and 4b is an individual resistance 8a and 8b, these resistances being in each case preferably of just sufficient value 65 to insure aperiodicity of flow upon closing of the switch 5; it will be understood that if desired these resistances may be made inherent in the windings of the respectively associated electromagnets.

All the electromagnets 4a are connected to 70 ground through the common resistance 13a; similarly all the electromagnets 4b are connected to ground through the common resistance 13b. Each of these resistances is preferably variable 75 from a low or zero value to a relatively high value.

Their function is the regulation of the relative strengths of excitation effected by the respective electromagnets 4a and 4b of any string whose associated key 5 is depressed. Such regulation makes possible simultaneous impulse excitations, at different points along the string, of controlled relative strengths.

It is well understood that when a string is excited by impulse excitation the form of its vibration—i. e., the relative amplitudes and phases of its different partial vibration components—is determined by the point along the string whereat the excitation is effected. Thus if any of the strings 1 be at one time excited essentially by only the associated electromagnet 4a (the resistance 13b being adjusted to a relatively high value) and at another time be excited essentially by only the associated electromagnet 4b (the resistance 13a being adjusted to a relatively high value), its vibrations in these separate cases will be of respectively different form; each partial vibration component will occur in a respectively different amplitude and phase. If the string be subjected to simultaneous excitation at full strength by each of the associated electromagnets 4a and 4b 25 (the resistances 13a and 13b being adjusted to their minimum values), each partial component in the ensuing vibration will be of a new amplitude (as well as phase), its amplitude at any instant being the algebraic sum of the amplitudes 30 at that instant of that partial in the separate vibrations abovementioned; a new vibrational form results. Further if the string be subject to simultaneous excitation at different fractional strengths by each of the associated electromagnets (the resistances 13a and 13b being adjusted for example to respectively different values) each partial component in the ensuing composite vibration will be of still a new amplitude (as well 35 as phase), since its instantaneous amplitudes are 40 determined by the algebraic addition of modified separate instantaneous amplitudes. While I view only the relative amplitudes (and not phases) of the several partial components as being of particular importance in the composite vibration, the 45 differences in phase as well as amplitude of each one component in the respective separate vibrations are of great importance in producing distinctive differences in relative amplitudes in the composite vibration.

It will be understood that the number of separate electromagnets which may be employed with each string is not limited to two, and that still greater variations in relative amplitudes of the several partial components in the composite 55 vibration may be produced by the use of a greater number of electromagnets with individual excitation strength control.

Another method of extending the range of possible variation of relative partial amplitudes in 60 the composite vibration lies in the control of direction, as well as of strength, of the excitation produced by one or more of the electromagnets associated with each string. It will be understood that this provides phase control over all the partial components in the separate vibration resulting from excitation by that electromagnet. A non-limitative example of means for controlling this direction has been illustrated in Figure 4. Herein each electromagnet 4b is complemented 70 by another electromagnet 4b' in spaced relation to the same string portion but on the opposite side of the string. A terminal of each electromagnet 4b' is connected to a terminal of the associated electromagnet 4b and to the key-switch 75

5 through the resistance 8b. The other terminals of all the electromagnets 4b' are connected together and to a first extremity of the potentiometer 13b', which is substituted for the resistance 13b of Figure 3. The other terminals of all the electromagnets 4b are connected in common to the other extremity of the potentiometer 13b'. The movable contact 13b'' of the potentiometer is connected back to ground, as was the lower-10 shown extremity of the resistance 13b of Figure 2. The operation of the electromagnets 4b and 4b' and of their associated control is now as follows:—

If the movable contact 13b'' is adjusted to the center of the potentiometer 13b' there will flow, upon closing of the switch 5 associated with any string 1, equal quantities of electricity in the associated electromagnets 4b and 4b'; these electromagnets are mutually similar and arranged upon similar energization to urge the string equally in opposite directions. Therefore the effective excitation of the string by these electromagnets in combination is zero. But as the contact 13b'' is moved toward either extremity of the potentiometer 13b' the energization, upon closing of any switch, of the electromagnet connected to that extremity is increased and that of the other reduced, and the strength of excitation by the combination therefore increased from its zero value. The same is true for movement of the contact toward the other extremity; but obviously the direction of excitation will in this case be opposite. Thus in the illustrated arrangement the potentiometer 13b', and in particular its contact 13b'', provides the desired control of excitation direction for the electromagnet combinations 4b—4b'; at the same time it provides a very satisfactory control of excitation strength alternative to the previously illustrated control. Such an arrangement may of course be employed with other or all of the electromagnets, being illustrated with the electromagnets 4b only by way of example.

In Figure 4 I also show a further feature of my invention, which includes the selective use of the same electromagnets for impulse or sustained oscillatory excitation of the strings. Thus the blades 5' of the several key-switches 4 are normally—i. e., for impulse excitation—connected to the respective condensers 3 through the individual switches 15. These switches 15 are linked together and may be simultaneously thrown at will to disconnect the switch blades 5' from the condensers 3 and to connect them each to a terminal of a respective generator 16, the other terminals of which generators may be connected together and to ground. The generators 16 may be of any suitable form to generate electric oscillations, in each case preferably of a fundamental frequency coinciding with that of the associated string. Such generators themselves, and their use in connection with electromagnets to vibrate the strings, are well known and are therefore not herein described in detail. In the combination illustrated not only are the same electromagnets employed for both types of excitation, but the same playing means—i. e., key-switches 5—and the same vibrational form control means—e. g., resistance 13a and potentiometer 13b—are employed in the two cases.

The oscillatory excitation just outlined differs from the oscillatory excitation obtained in the circuit of Figure 1 with switch 18 closed in that it is sustained rather than damped. For string vibrations of relatively short duration this dis-

tinction is not of great importance and the circuit of Figure 1 is to be preferred on the ground of simplicity. If string vibration of relatively great duration at substantially constant amplitude is desired, however, the circuit of Figure 4 is to be preferred.

It is to be noted that when the string is oscillatorily excited the harmonic structure of its vibration with any given setting of the controls (13a and 13b) will not necessarily be similar to the harmonic structure resulting from impulse excitation with the same control settings; these controls, however, may still be employed with the oscillatory excitation to produce significant changes of harmonic structure of the vibration.

In Figure 4 I show mechanico-electro-acoustic translating apparatus for translating the string vibrations into sound; the strings 1 are therefore in this figure shown passing over a second triangular bar 2' instead of over the bridge 10 of Figure 1. This bar 2' is intended to be electrically conductive, and thus forms an electrical connection to each of the strings 1. Adjacent and in slight spaced relationship to the several strings 1 is provided a conductive strip 20 of small cross-section. This may be cemented to an edge of an insulating strip 21 and this secured in any convenient manner in position to maintain the conductive strip in the mentioned relationship to the strings. Obviously a small capacity is formed between the conductive strip 20 and each of the strings; and these several capacities in parallel with each other form a total capacity from strip to strings. In this total capacity may be maintained a charge relatively incapable of rapid variation. For this purpose the strip 20 is connected through a high resistance 22 to one terminal of a high voltage battery or other source 30, the strings (through the medium of the bar 2') being connected to the other terminal of the battery. If now any string be vibrated toward and away from the conductive strip 20 the total capacity above mentioned will be varied. By virtue of the relative constancy of the charge therein the voltage thereacross will vary in accordance with the frequency and waveform of the string vibration, and the voltage across the high resistance 22 will similarly vary.

For responding to voltages across the resistance 22 there is provided a thermionic vacuum tube 25. The cathode of this tube may be energized in any suitable manner; its anode current may be supplied as from a battery or other source 31; and its cathode may be maintained at a potential slightly positive with respect to the negative terminal of source 31 by the flow of anode current through condensingly-by-passed resistance 26. The grid of tube 25 may be biased slightly negative with respect to the cathode by connection thereof through the high resistance or grid leak 24 to the negative terminal of source 31. The resistance 22 is connected through the condenser 23 across the grid leak 24.

In the output circuit of tube 25 may be connected in cascade amplifier 27, potentiometer 28 and loudspeaker 29. Electrostatic shielding schematically shown as 32, may advantageously be provided at least partially around the strip 20, resistances 22 and 24, tube 25, and immediately associated elements. Obviously electric oscillations appearing across resistance 22—i. e., translated from string vibration—will be amplified by tube 25 and amplifier 27, may be controlled in respect of amplitude by potentiometer 28, and are translated into sound by loudspeaker 29.

In the spring exciting systems shown in Figures 1 through 4 the condenser forms a means for limiting the flow of electricity through the electromagnet. In other embodiments of my invention, however, other means for producing this effect are employed, and one such means is illustrated in Figure 5. This means is part of a flow control system including the key 41, and comprises a variable resistance of value which is normally high and is momentarily reduced upon key depression. The key 41 is pivoted as at 42 and has the rearward extension 41' weighted so as normally to rest on felt 43. The key is depressible to raise the extension 41' and impinge the same against the stop 44. Above the key extension 41' is provided the variable resistance element comprising the pile 48 of discs of carbon or other resistance material, the pile normally having a very high or preferably infinite resistance. It may be retained in the vertical hole 49 in insulating block 50, resting on the plunger 51 which in turn is normally supported in position just entering the bottom of hole 49 by the leaf spring 52 secured to the bottom of the block 50. To the block 50 and across the top of the hole 49 may be secured a conductive plate 53. When the plunger 51 occupies its normal position the pile 48 is in no compression and its top is preferably in very slightly spaced relationship to the bottom of plate 53; its resistance is therefore infinite. If the plunger 51 be raised, however, the top of the pile 48 will be raised into contact with the stationary plate 53 and the pile placed in compression and its resistance thus lowered.

The upward movement of the key extension 41' is intended to raise the plunger 51. In order, however, to render this raising momentary only the stop 44 is arranged to prevent impingement of the key extension against the plunger, and there is interposed between the key extension and the plunger a weight 45. This is normally carried by the key extension; but upon impingement of the latter against stop 44 the momentum of the weight causes it to continue its upward motion and momentarily to raise the plunger 51 and compress the pile 48. In order that the weight may invariably return to the same position relative to the key extension, it may be connected to the latter by a light leaf spring 46, which in turn is secured to an upward boss 41'' formed from the extension 41'. Felt 47 may be provided on top of the extension 41', and the spring 46 may normally bear thereagainst, the felt serving to suppress tendencies of the spring and weight to oscillate with respect to the extension. For electrical terminals of the variable resistance element there may be employed the plate 53 and the spring 52. In series therewith may be connected the source 6, with its potentiometer 9 if desired, the electromagnet 4 and the resistance 8. The last now serves only as a control of excitation strength, over and above such control as may be effected by key velocity as hereinafter mentioned.

Illustrative of a slightly modified arrangement for influencing the string by the electromagnet 4 I have shown the electromagnet in Figure 5 again provided with a fixed core 4', but arranged upon energization to attract an armature 55 secured to the pivoted shank 56 of the hammer 57. This attraction moves the hammer shank about its pivot 58 and the momentum thus imparted to the hammer moves the same into contact with the string. By the time of such contact the pile 48 will have re-assumed a substantially infinite resistance and no substantial attraction of elec-

tromagnet for armature will remain, wherefore the hammer will rebound back to its normal or illustrated position wherein the shank 56 rests against the felted stop 59.

An important feature of this embodiment of my invention resides in its responsiveness to "touch", or key velocity. It will be obvious that variations in this velocity will produce variations in the momentum of the weight 45, and therefore in turn variations in the degree of compression of the pile 48, and of the speed and value with and to which its resistance will be reduced. Accordingly the current supplied to the electromagnet is of an amplitude and a rate of rise each greater the greater the key velocity, and the strength of hammer blow on the string is thus responsive to touch.

In Figure 6 I show another embodiment of my invention also adapted for touch responsiveness. The key 41 is provided, as in Figure 5. Further as in that figure a weight is employed, this being shown however as the electrically conductive weight 45' supported by the light leaf spring 46' to the insulating bushing 62 on block 50. With the key in its normal position the weight 45' is lightly urged by the spring 46' against felt 61 secured to the top of the key extension 41'. On the top of the weight 45' is formed a contact button 45''. Above this button is another contact button 52'' formed on the spring 52', which is secured to the block 50. The height of the second contact button 52'' is such that a slow depression of the key 41 and raising of its extension 41' into impingement against the stop 44 will raise the weight 45' and the contact button 45'' into a position slightly short of contact with the button 52''. If the key be depressed with any appreciable velocity, however, the weight 45', upon impingement of the extension 41' on the stop 44, will continue its upward motion and bring the contact button 45'' into contact with the button 52''. Thereupon the spring 52' will be temporarily flexed upwardly in a degree increasing with the velocity of the key depression, the two buttons remaining in mutual contact during the period of this flexure. This period of course depends on the degree of flexure and hence on the velocity of key depression.

Viewing the contact buttons and their supporting springs as constituting a switch, it will be obvious that upon key depression this switch is closed for a period dependent on the velocity of the depression. The switch is serially connected between the battery 6 and the electromagnet 4, and the latter is therefore energized while the switch is closed. In this embodiment the electromagnet is illustrated, as in Figure 2, as having the movable core 4'' surmounted with the hammer head 4'''. The period during which the switch remains closed in response to key depression of substantially maximum possible velocity is preferably not in excess of the time interval required for the core 4'' to rise to a centralized position in the electromagnet in response to that depression, since the continuance of flow of electricity after the core has reached this position is a deterrent and not an aid to impingement of the hammer head 4''' against the string. If this limitation be observed it will be appreciated that as key velocity is reduced from maximum, the attendant reduction of period during which the switch remains closed will produce a corresponding reduction in the integrated force applied to the core 4'' and hence in the strength of the impact of hammer head 4''' on the string.

While Figures 5 and 6 are fundamentally adapted to use with any form of vibration-sound translation, I have shown therein the conductive strip 20, supported by the insulating strip 21, in spaced relationship to the string 1. The string 20 may be electrically connected to the elements 22 and 23 illustrated in Figure 4, thereby providing mechano-electro-acoustic translation of string vibration into sound.

10 I particularly prefer vibration-sound translation of the mechano-electro-acoustic form rather than of the direct mechano-acoustic form, in connection with the excitation arrangements which I have shown not only in Figure 5
 15 but also in previous figures, because of its far more modest demands for energy of string vibration and hence more modest requirements for energy impartation to the string by the excitation. In the case of direct mechano-acoustic
 20 translation—e. g., as illustrated by the soundboard 11 in Figure 1—energy exceeding that of the sound to be produced by a given string must be passed into or out of the associated condenser 3 upon closing of the switch 5. No such requirement exists in the case of the mechano-electro-acoustic translation—e. g. as illustrated in Figure 4—because the sound energy is supplied by the amplifier 27, being controlled rather than produced by the string. Indeed, with mechano-
 25 electric translating apparatus operating on the basis of inductive influencement by the string of an adjacent member—in Figure 4 the conductive strip 20—substantially no energy is lost by the vibrating string other than that required to over-
 30 come the self-resistance of the string to vibration; the translating apparatus is influenced solely by the displacement and not by the force of the string. In such cases it is unnecessary to employ strings of high mass at high tensions;
 35 and in order that the maximum displacement be produced by excitation of a given strength I prefer to employ strings 1 of relatively low mass held under relatively low longitudinal tension.

As to the various arrangements which I have shown of the electromagnet 4 with respect to the string 1, these are in general interchangeable, subject to the limitation that the arrangement shown in Figure 1 (and embodied in Figures 3 and 4) is intended for use when an oscillatory
 45 flow takes place through the electromagnet.

While the strings 1 represent a preferred form of vibrator, my invention is obviously not limited thereto, as any form of tuned vibrator may obviously be substituted therefor. As to the principles of operation of the plurality of electromagnets opposite respectively different portions of the vibrator, however, these are in general applicable only to vibrators whose vibrational forms in different portions are inherently different. It is of course obvious that in cases wherein the string or other vibrator is directly attracted by the electromagnet 4 it must be of steel or other magnetic material; and further that in cases wherein the particularly illustrated mechano-electro-acoustic translation is employed the strings or other vibrators should be electrically conductive.

It will be understood that while I have described my invention in terms of specific embodiments thereof, I intend that the scope of the invention be not limited by the details of these embodiments, but rather gauged by the following claims.

I claim:—

75 1. In a musical instrument including a tuned

vibrator: impulse exciting means for said vibrator comprising an electrically operable exciting device associated with said vibrator, a source of electricity, electric flow control means connected with said source and said exciting device and operable at will to produce a flow through said exciting device of electricity from said source, and means included in said flow control means for limiting the duration of said flow.

2. In a musical instrument including a tuned 10 vibrator: impulse exciting means for said vibrator comprising an electromagnet in spaced relationship to said vibrator, a source of electricity, electric flow control means connected with said source and said electromagnet and operable at 15 will to produce a flow through said electromagnet of electricity from said source, and means included in said flow control means for limiting the duration of said flow.

3. In a musical instrument including a tuned 20 vibrator: impulse exciting means for said vibrator comprising a condenser, means for normally maintaining said condenser in a given state of charge, an electrically operable exciting device associated with said vibrator, and means operable at will to produce through said device a predetermined change in the charge of said condenser.

4. In a musical instrument including a tuned 30 vibrator: means for exciting said vibrator comprising a condenser, means for normally maintaining said condenser in a given state of charge, an electromagnet in spaced relationship to said vibrator, and means operable at will to produce through said electromagnet a predetermined 35 change in the charge of said condenser.

5. In a musical instrument including a tuned 40 vibrator: means for exciting said vibrator comprising a condenser; means for normally maintaining therein an electrical charge; an electrically operable exciting device associated with said vibrator; a normally open circuit serially comprising said condenser and said electromagnet; and means included in said circuit for closing the same at will whereby to discharge said 45 condenser through said electromagnet.

6. In a musical instrument including a tuned 50 vibrator: means for exciting said vibrator comprising a condenser; an electrically operable exciting device associated with said vibrator; a normally open circuit serially comprising said condenser, said electromagnet, and a source of current; means included in said circuit for closing the same at will whereby to charge said condenser through said electromagnet; and means 55 operative upon opening of said circuit to discharge said condenser.

7. In a musical instrument including a tuned 60 vibrator: exciting means therefor selective with respect to characteristics of the excited vibration, comprising a condenser; means for normally maintaining therein an electrical charge; an electromagnet in spaced relationship to said vibrator; a normally open circuit serially comprising said condenser, said electromagnet and electrical resistance; means included in said circuit for closing the same at will whereby to discharge said condenser through said resistance and electromagnet; and means for controlling 65 the value of said resistance to control the nature of said discharge.

8. In a musical instrument including a tuned 70 vibrator: exciting means therefor selective with respect to characteristics of the excited vibration, 75

- comprising a condenser; means for normally maintaining said condenser discharged; an electromagnet in spaced relation to said vibrator; a normally open circuit serially comprising said condenser, said electromagnet, electrical resistance and a source of current; means included in said circuit for closing the same at will whereby to charge said condenser through said electromagnet; and means for controlling the value of 5 said resistance to control the nature of said discharge.
9. In a musical instrument including a tuned vibrator: means for exciting said vibrator comprising a condenser, means for normally maintaining said condenser in a given state of charge, a plurality of electromagnets in spaced relationship to respectively different portions of said vibrator, and means operable at will to produce through said electromagnets simultaneously a 10 predetermined change in the charge of said condenser.
10. In a musical instrument including a tuned vibrator: impulse exciting means whereby said vibrator may be selectively excited into vibration 15 of a plurality of different forms, comprising a plurality of electrically operable exciting devices respectively associated with a plurality of different portions of said vibrator; a source of electricity; electric flow control means connected 20 with said source and said exciting devices and operable at will to produce a flow through said electromagnets of electricity from said source; means included in said flow control means for limiting the duration of said flow; and adjustable 25 means respectively associated with said exciting devices for varying the relative portions of said flow respectively passing therethrough.
11. In a musical instrument including a tuned vibrator: means for exciting said vibrator selectively to vibration in a plurality of different vibrational forms, said means comprising a plurality of electromagnets respectively in spaced relationship to different portions of said vibrator; means operable at will to pass a current through 30 said electromagnets simultaneously; and adjustable means connected with the several said electromagnets for controlling the portions of said current respectively passing through the several 35 said electromagnets.
12. In a musical instrument including a tuned 40 vibrator, an electromagnet in spaced relation to a portion thereof, and means for passing a current through said electromagnet whereby to excite said vibrator into vibration; means for controlling the amplitude of said vibration comprising a second electromagnet in spaced relation to said portion of said vibrator but on the opposite side thereof from said first electromagnet, means for passing a current through said 45 second electromagnet simultaneously with the passage of current through said first whereby oppositely to excite said string; and means for controlling the relative amplitudes of said two currents.
13. In a musical instrument including a tuned 50 vibrator: means for exciting said vibrator in controlled degree and direction comprising two electromagnets in spaced relation to a single portion of said vibrator but on opposite sides thereof; means for passing simultaneous currents through 55 said electromagnets in respective directions to create mutually opposing fields; and means for controlling the relative amplitudes of said currents.
14. In a musical instrument including a plurality of tuned vibrators: vibrator exciting means selective with respect to characteristics of the excited vibrations, comprising a plurality of electromagnets respectively in spaced relation to said vibrators; a plurality of playing switches respectively in series with said electromagnets; a plurality of sources of current pulses; a plurality of electric oscillation generators of frequencies respectively similar to those of said vibrators; and 10 means selective with respect to said sources and said generators, for connecting either said pulse sources respectively or said generators respectively to said electromagnets and said playing switches.
15. In a musical instrument including a tuned 15 vibrator; an electrically operable exciting device associated therewith, and a source of current: means for passing a current of limited duration from said source through said device, said means comprising a resistance electrically interposed between said source and said device, the value of said resistance being normally high and being reduceable in response to pressure on said resistance; a stop member; a key movable to produce 20 impingement of a portion thereof against said stop member; and a weight normally carried by a portion of said key and adapted upon said impingement to continue movement and to impinge 25 against and press upon said resistance.
16. In a musical instrument including a tuned 30 vibrator, an electrically operable exciting device, and a source of current: means for passing a current of limited duration from said source through said device, said means comprising a key and a stop member therefor, said key being movable to produce impingement of a portion thereof against said stop member; a weight arranged for movement with said key until said impingement occurs and for further movement in response to its own 35 momentum; and a normally open switch electrically interposed between said source and said device, said switch having a portion disposed in the path of said further weight movement and being adapted to be closed by and during impingement 40 of said weight against said switch portion.
17. In a musical instrument, the combination 45 of a key and a stop member therefor, said key being movable to produce impingement of a portion thereof against said stop member; a weight arranged for movement with said key until said impingement occurs and for further movement in response to its own momentum; a source of current; and a current passing device disposed in the path of said further weight movement and 50 responsive to impingement thereagainst of said weight.
18. In a musical instrument including a tuned 55 vibrator, an electrically operable exciting device, and a source of current: means for passing a current of limited duration from said source through said device, said means comprising a key and a stop member therefor, said key being movable to produce impingement of a portion thereof against said stop member; a weight arranged for movement with said key until said impingement occurs and for further movement in response to its own momentum; and a current passing device 60 electrically interposed between said source and said device, mechanically disposed in the path of said further weight movement, and responsive to impingement thereagainst of said weight.

BENJAMIN F. MIESSNER.
